US0D1108357S

(12) **United States Design Patent** (10) Patent No.: **US D1,108,357 S**
(45) Date of Patent: ** Jan. 6, 2026

(54) **CHARGING PANEL**

(71) Applicant: **SHENZHEN MAMMOTION INNOVATION CO., LIMITED**, Shenzhen (CN)

(72) Inventors: **Shaojie Chen**, Guangdong (CN); **Jiaqian Lin**, Guangdong (CN)

(73) Assignee: **Shenzhen Mammotion Innovation Co., Limited**, Shenzhen (CN)

(**) Term: **15 Years**

(21) Appl. No.: **35/522,600**

(22) Filed: **Aug. 21, 2024**

(80) **Hague Agreement Data**

Int. Filing Date: **Aug. 21, 2024**
Int. Reg. No.: **DM/240822**
Int. Reg. Date: **Aug. 21, 2024**
Int. Reg. Pub. Date: **Oct. 11, 2024**

(30) **Foreign Application Priority Data**

Mar. 6, 2024 (CN) 202430112399.7

(51) LOC (15) Cl. **13-02**

(52) U.S. Cl.

USPC **D13/107**; D13/108

(58) **Field of Classification Search**

USPC D13/103, 107, 108, 110, 118, 124, 184, D13/133; D14/434

CPC H02J 7/00; H02J 7/0013; H02J 7/0044; H02J 7/1423; H02J 50/12

See application file for complete search history.
